Primary Examiner — Marianne Pandozzi(57) **CLAIM**

The ornamental design for an article of tableware, as shown and described.

DESCRIPTION

FIG. 1 is a perspective view of an article of tableware; FIG. 2 is a front elevation view thereof; the rear elevation view being a mirror image thereof; FIG. 3 is a left side elevation view thereof; FIG. 4 is a right side elevation view thereof; FIG. 5 is a top plan view thereof; and, FIG. 6 is a bottom plan view thereof. The broken lines in FIG. 6 are included for the purpose of illustration and form no part of the claimed design.
